UNITED STATES PATENT OFFICE.

GEORGE W. BENTON, OF CONNEAUT, OHIO.

METHOD OF AND MECHANISM FOR FORMING SPLIT D HANDLES.

Application filed February 26, 1924. Serial No. 695,233.

To all whom it may concern:

Be it known that I, GEORGE W. BENTON, a citizen of the United States, and a resident of Conneaut, county of Ashtabula, and 5 State of Ohio, have invented a new and useful Improvement in Methods of and Mechanism for Forming Split D Handles, of which the following is a specification, the principle of the invention being herein explained and the best mode in which I have contemplated applying that principle, so as to distinguish it from other inventions.

As is well-known, so-called split D-handles are characterized by having one end of the 15 haft or stem split for a short distance and the portions on each side of the split formed into diverging arms between which is secured the grip bar. The opposite end of such handle, to which the implement, e. g. 20 a shovel, spade or the like, is suitably attached, is ordinarily bent in the form of a double curve so as to offset such implement with respect to the main body of the haft or stem. Heretofore in the manufacture of 25 handles of the type in question, the practice has been to form the split end in one operation and then to bend the other end as a separate operation, the order of the operations being immaterial. Inasmuch as both 30 ends are formed in dies or molds and require to be held in such dies until the wood has thoroughly dried out and the ends thus caused to set in the form desired (the wood, of course, requires to be steamed or otherwise softened to permit the bending there- 35 of), the performance of these operations separately not only involves a duplication of effort but is complicated in the case of the second operation by the fact that the previously formed end is encased in a die or 40 mold which has thus to be left in place.

It becomes necessary in fact, in performing these operations, to laterally grip the haft or stem at an intermediate point with sufficient force to substantially prevent end- 45 wise movement of the handle, the result being that frequently the handle is marred by the gripping means employed or due to its slipping in such means.

50 The object of the present invention is to provide a machine in which both bending operations may be performed simultaneously i. e., the split handle end proper is formed at the same time that the opposite end is bent into the offset form desired. Incidentally to such forming operations,

pressure is accordingly applied against both ends of the handle and in approximately equal amounts so that it is unnecessary to employ any intermediate gripping means to 60 prevent endwise movement of the handle. The performance of both operations at the same time furthermore effects a material saving in time and power, since obviously no more force is required than where one 65 end at a time is being operated upon.

To the accomplishment of the foregoing and related objects, the invention, then, consists of the steps and means hereinafter fully described and particularly pointed out 70 in the claims, the annexed drawings and the following description setting forth in detail certain mechanism embodying the invention, such disclosed means constituting, however, but one of various mechanical 75 forms in which the principle of the invention may be used.

In said annexed drawings:—

Fig. 1 is a side elevation and Fig. 2 a plan view of a machine embodying my present improvements.

The operative parts of the machine are suitably mounted on a bed 1, supported at a convenient elevation by legs 2. For the purpose of receiving and properly locating the handle with respect to the forming dies or molds, a clamp is mounted on said bed at a point approximately midway between its ends, such clamp consisting of a fixed jaw 3 and a movable jaw 4 pivotally attached to said fixed jaw and adapted to be pressed thereagainst by means of a lever 5, as will be readily understood. The bed is formed with a central longitudinal opening 6 that extends substantially its entire 85 length and aligned with such opening are two sets of guides 7, 7, and 8, 8, one set being located on each side of the clamping means just described. Slidably held between guides 7, 7, is a block 9, the upper face of which is adapted to have detachably secured thereto a horizontally split mold or die 10 of the type regularly employed in forming the split end into diverging arms of desired 90 curvature. Similarly, slidably held between guides 8, 8, is another block 12 adapted to have detachably secured thereto a vertically split die or mold 13 of the type regularly used for forming or bending the butt end 100 of the handle, i. e., the end to which the implement is designed ultimately to be attached.

Suitable means are provided for simultaneously advancing the slide blocks 9 and 12 towards each other and for similarly simultaneously retracting same. In the preferred form shown, such means include two segmental disk cams 14 and 15, fixedly secured to a transverse shaft 16 that is journaled in suitable bearings on the bed of the machine adjacent one end of such bed (the left-hand end as shown in Figs. 1 and 2). These cams are preferably of helical outline but being located 180 degrees apart, are adapted to exert a pushing action in opposite directions. Cam 14 co-operates with a roller 17 on one end of a bar 18 that extends longitudinally of the slot in the bed of the machine and is pivotally secured at its other end between two ears 19 that depend from slide block 9. The other cam 15 co-operates with a roller 20 directly mounted on the adjacent end of slide block 12.

As a result of the foregoing construction, it will be seen that as the shaft 16 rotates in a clockwise direction, viewing the machine from the side shown in Fig. 1, the bar 18 and thus slide block 9 will be pulled towards the left at the same time that the slide block 12 is pushed towards the right. For the purpose of retaining rollers 17 and 20 in contact with their respective cams, a counterweight 21 is connected by means of a cable 22 that passes over a pulley 23 with the slide block 9, while another counterweight 24 is connected by means of a cable 25 that passes over a pulley 26 mounted at the opposite end of the bed with slide block 12.

The shaft 16 that carries the cams may be driven in any desired manner. As shown, an electric motor is connected with said shaft through suitable reduction gearing, as need not be described in detail, the reduction preferably being considerable so that a motor of low horse-power may be employed and so that the movement of the slide blocks with the dies carried thereby respectively may be at the necessary slow speed in order properly to force the dies onto the respective ends of the handle without damage to the latter.

In operating the machine, the straight unformed haft or stem, which, however, has its one end split, as hereinbefore described, is placed between clamp jaws 3 and 4, the slides 9 and 12 being in fully retracted position and having a set of dies 10 and 13 respectively secured thereto. The dies are then forced onto the corresponding ends of the stem with the result that these are appropriately formed by the movement of the slides towards each other produced upon rotation of shaft 16. On completion of such movement, the stem is unclamped and removed with the dies or molds which are previously

detached from the corresponding slides, a fresh set of such dies is secured to each of the slides, and another handle placed in position for the next operation as soon as the slides have been sufficiently retracted. 70

Other modes of applying the principle of my invention may be employed instead of the one explained, change being made as regards the means and the steps herein disclosed, provided those stated by any one of 75 the following claims or their equivalents be employed.

I therefore particularly point out and distinctly claim as my invention:

1. The method of forming split D-handles 80 which consists in placing the straight haft with its one end split between two relatively movable dies respectively adapted when forced upon the ends of such haft to spread and form the portions of such split end and to bend the other end; and simultaneously moving said dies thus to force the same upon such ends.

2. In mechanism of the character described, the combination of two spaced supporting members movable towards and from each other; and dies detachably secured to said members respectively and adapted when forced upon the respective ends of a straight haft split at its one end to spread 85 and form the portions of such split end and to bend the other end. 90

3. In mechanism of the character described, the combination of two spaced supporting members movable towards and from each other; dies detachably secured to said members respectively and adapted when forced upon the respective ends of a straight haft split at its one end to spread and form 100 the portions of such split end and to bend the other end; and means adapted alternately simultaneously to advance said supports towards each other and draw the same apart. 105

4. In mechanism of the character described, the combination with a suitable bed; of two aligned sets of guideways thereon; members slidably mounted on said guideways, respectively, so as to be movable towards and from each other; a handle engaging and holding device located between said sets of guide-ways; dies detachably secured to said members respectively and adapted when forced upon the respective ends of a straight haft split at its one end to spread 110 and form the portions of such split end and to bend the other end; and means adapted alternately simultaneously to advance said supports towards each other and draw the same apart. 115

5. In mechanism of the character described, the combination with a suitable bed; of two aligned sets of guideways thereon; members slidably mounted on said guideways, respectively, so as to be movable to- 120

wards and from each other; a handle engaging and holding device located between said sets of guide-ways; dies detachably secured to said members respectively and adapted 5 when forced upon the respective ends of a straight haft split at its one end to spread and form the portions of such split end and to bend the other end; means adapted alternately simultaneously to advance said 10 supports towards each other and draw the same apart, said means including a rotatable shaft transversely journaled in said bed beyond one set of guide-ways; a disk cam fixed to said shaft and directly co-operative with the adjacent slidable member 15 with the adjacent slidable member to push the same towards the other member, a longitudinally extending bar connected with such other member, and a second disk cam fixed to said shaft and co-operative with said rod to pull the member thus connected 20 towards said first member.

6. In mechanism of the character described, the combination with a suitable bed; of two aligned sets of guideways thereon; 25 members slidably mounted on said guideways, respectively, so as to be movable towards and from each other; a handle engag-

ing and holding device located; dies detachably secured to said members respectively and adapted when forced upon the respective ends of a straight haft split at its one end to spread and form the portions of such split end and to bend the other end; means adapted alternately simultaneously to advance said supports towards each other and 30 draw the same apart, said means including a rotatable shaft transversely journaled in said bed beyond one set of guide-ways; a disk cam fixed to said shaft and directly co-operative with the adjacent slidable member 35 40 with the adjacent slidable member to push the same towards the other member, a longitudinally extending bar connected with such other member, a second disk cam fixed to said shaft and co-operative with said rod to pull the member thus connected 45 therewith towards said first member, and counterweights connected with said members tending to move the same oppositely to the direction of movement imparted by said cams.

Signed by me this 20th day of February, 1924.

GEORGE W. BENTON.
